ATTORNEY

UNITED STATES PATENT OFFICE.

EDWARD FRANK, OF BERKELEY, CALIFORNIA.

SHOE TIP.

Application filed August 18, 1926. Serial No. 129,999.

This invention resides in the provision of a novel form of protecting tip for the ends of shoes, which tip is constructed so that it may be readily applied to all sizes of shoes and secured in place without necessitating the loosening of the sole or in any way changing the construction of the shoe.

The present day form of metal shoe tip designed to prevent scuffing of the toes of shoes is only applicable to shoes in which the toe cap is nailed to the welt or sole and in attaching this type of tip it is necessary to loosen the welt and toe cap or to remove the nails. In shoes having the toe cap sewed to the welt, the attachment of the present day form of metal tip is not possible. Another objection is that different sizes of tips must be used to fit different sizes of shoes.

The shoe tip of my invention is not only applicable in its one piece and one size form to shoes of all sizes, but can be fitted to sewed and nailed shoes with equal facility and in either instance without necessitating loosening the fastenings between the toe cap and the welt or in any way modifying or changing the construction of the shoe.

The tip of my invention is constructed of rubber preferably, but may be made of any compressible, resilient and bendable substance of this nature. It may be made up in straight lengths and cut in desired lengths, depending upon the size of the shoe. The shape of the strip is such that when the strip is bent to fit around the front of the toe and on the top of the welt, it will closely conform to the welt and toe and may be readily nailed or otherwise fastened in place so that a portion thereof extends upward against the tip of the toe cap and protects said cap from being scuffed and worn.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a perspective view of my tip as when applied to a shoe.

Fig. 2 represents a fragmentary longitudinal sectional view through the toe of the

shoe showing the tip of my invention as when applied thereto.

Fig. 3 represents a perspective view of a strip of the tip material of especial shape and form whereby suitable lengths may be cut off to provide the desired tips.

In the embodiment of the invention shown in the accompanying drawing, the shoe tip forming material is preferably made up in the form of a straight length or strip of rubber or some other suitable compressible, resilient and bendable material, said strip being indicated by the numeral 1 in Fig. 3. This strip comprises an upstanding portion 2 which is of concavo-convex form or may be curved on one side only so as to conform to the curvature of the shoe tip. Along the lower longitudinal edge of the strip on the front side thereof, is a lateral flange 3. In providing a shoe tip of this invention, a piece of the material of the desired length is cut off for each shoe and then bent around the toe 3' on top of the welt 4 as shown in Figs. 1 and 2. The curved inner face of the upstanding portion of the strip will engage the curved end of the toe cap and conform closely thereto whereas the flange 3 will extend outward on top of the welt and provide a means for nailing the tip in place, the nails being indicated by the numeral 5. The thickness of the tip may be varied as desired, it being unnecessary to provide a very thick piece when rubber is employed as the material of which the tip is formed. The height of the tip may be varied as desired also, but if the tip extends approximately half way up on the point of the toe, this is usually sufficient.

The advantage of the tip of this invention is that it may be readily made to conform to shoes of different sizes and may be easily and quickly attached without altering the construction of the shoe in any particular. When in place it remains more or less inconspicuous but is nevertheless so positioned as to effectively protect the toe of the shoe against being scuffed or unduly worn. The lower inner edge of the strip will fit closely between the toe cap and welt and the tip therefore assists in making this portion of the shoe weatherproof. Another advantage of the invention is the provision for supplying the shoemakers with the tip forming material in straight lengths, cut or molded in the shape shown and described thus making it an easy matter to cut off

lengths of material and by a quick operation securely fasten them in place so as to provide effective protective tips upon the shoes.

I claim:

5 A protective tip for shoes comprising a normally straight rubber strip having its inner face curved in a vertical plane to conform to the curvature of and to engage the toe of the shoe, a laterally extending flange 10 formed integral with the strip on the lower

edge thereof and extending forwardly from the outer face of the strip, said strip being adapted to be bent into engagement with the toe of a shoe so as to conform to the curve of the toe and to have the lateral flange rest upon the projecting portion of the sole of the shoe, said lateral flange being adapted to have fastening elements driven therethrough to hold the strip in place.

EDWARD FRANK.
